L. D. HUBBARD

HOT PLATE

Filed Sept. 5, 1922

FIG. 1

FIG. 2

FIG. 3

Lemott D. Hubbard,

By

James L. Porto
Attorney

UNITED STATES PATENT OFFICE.

LEMOTT D. HUBBARD, OF UTICA, NEW YORK.

HOT PLATE.

Application filed September 5, 1922. Serial No. 586,359.

To all whom it may concern:

Be it known that LEMOTT D. HUBBARD, a citizen of the United States, residing at Utica, in the county of Oneida and State of New York, has invented new and useful Improvements in Hot Plates, of which the following is a specification.

This invention relates to hot-plates for ranges and proposes the construction of a simple and inexpensive device for supporting a cooking utensil upon a gas range and which is adapted to admit and enclose the naked flame from the burner of said range, whereby the heat of said flame is conserved in the hot-plate, the bottom and sides of the cooking vessel shielded from soot and a substantial economy made possible in the consumption of fuel.

One of the objects of the invention is the provision of a hot-plate closed at the top and provided with an annular flame chamber having an opening thereto on the underside to give access of the flame to said chamber.

Another object of the invention is the provision of vent apertures opening into said flame chamber on the underside of the hot-plate at points remote from the flame opening, to permit the flame to be drawn into said chamber.

A further object of the invention is the construction of a hot-plate having an upper imperforate wall of sheet metal serving as a support for a cooking vessel and being secured in spaced relation to a lower wall, enclosing with said wall a flame chamber, said lower wall being provided with a central opening and with a plurality of spacing lugs contacting with said upper wall and arranged around said central opening, being separated to afford communication between said opening and said flame chamber.

For a full understanding of the invention and the merits thereof and also to acquire a knowledge of the details of construction, reference is to be had to the following description and accompanying drawings, in which:—

Figure 1 is a perspective view of my improved hot-plate, a portion thereof being broken away.

Figure 2 is a plan view of the blank from which the lower portion of the hot-plate is stamped up.

Figure 3 is a cross section taken diametri-

cally through the hot-plate shown in Figure 1.

Referring now in detail to the several figures, the numeral 1 represents the upper wall of the hot-plate which is formed from a plane imperforate circular blank having a flange 2 thereof struck down at right angles to the main portion of the blank as shown in Figure 1. This part of the hot-plate is telescoped over the upturned flange 3 of the lower wall, the latter being formed from a similar although slightly smaller blank to that from which the upper wall is stamped, and having its peripheral edge upturned to form the flange 3. This blank is shown in Figure 2 and it will be observed that a central opening 4 is stamped out, likewise a circular series of apertures 5, the latter being arranged at points remote from the central opening 4. A plurality of spaced lugs 6 are formed on the peripheral edge of the opening 4 and are struck up at right angles as shown in Figure 1 to form spacing elements which contact with the upper wall 1 reinforcing the central portion thereof so as to prevent collapse of the same when it is carrying a cooking utensil. The upper and lower walls of the hot-plate enclose an annular flame chamber 7, and the lugs 6 are spaced apart so that the central opening 4 affords communication between said opening and said chamber for the passage into the latter of a flame entering the opening 4.

The flanges 2 and 3 of the upper and lower walls respectively are secured together as shown at 8, by turning the lower edge of the flange 2, which is made slightly longer than the flange 3, inwardly over the latter.

In operation, the hot-plate is placed over the burner of a gas range or stove and the cooking vessel placed on top of it. The flame from the burner enters the opening 4 and plays within the flame chamber 7. The vent apertures 5 permit the escape of the products of combustion and produce a draft which ensures the drawing of the flame into the flame chamber. All of the heat of the flame is confined to said flame chamber and to the walls thereof, none of it being dissipated into the air and up around the sides of the cooking utensil. The same amount of available heat may be obtained by using my improved hot-plates with a smaller flame than is possible without said

hot-plate, thus effecting a substantial economy in the amount of gas consumed. Furthermore, the sides of the cooking vessel are protected from being blackened or overheated by the products of combustion, and the handles of said vessels remain cool.

While I have shown in the preferred embodiment illustrated in the present drawings a form of construction of my improved hot-plate which is extremely simple and inexpensive to manufacture yet it is within the spirit of the invention to adopt such changes in structure, and variations in the details of the several features as is permitted by the scope of the claims.

Having described my invention what I claim as new and desire to secure by Letters Patent, is:—

1. A hot-plate comprising an upper imperforate wall provided with a peripheral flange and a lower wall having a peripheral flange and a flame opening surrounded by a plurality of spacing lugs, said upper wall being arranged with its flange telescoped upon the flange of said lower wall, enclosing a flame chamber, the lugs of said lower wall contacting with said upper wall and spaced apart affording communication between said flame opening and said flame chamber.

2. A hot-plate comprising an upper imperforate wall provided with a peripheral flange and a lower wall having a peripheral

flange, and a flame opening surrounded by a plurality of spacing lugs, said upper wall being arranged with its flange telescoped upon the flange of said lower wall, enclosing a flame chamber, the lugs of said lower wall contacting with said upper wall and spaced apart affording communication between said flame opening and said flame chamber, and said lower wall being provided with a plurality of vent apertures arranged remotely of said flame opening.

3. A hot-plate comprising a pair of walls secured together in spaced relation, the upper wall being formed from an imperforate blank of sheet metal having a downwardly extending peripheral flange, the lower wall being formed from a blank of sheet metal having an upwardly extending peripheral flange and being stamped with a central opening provided with a plurality of spaced lugs struck upwardly from the peripheral edge thereof and a series of vent apertures arranged remotely of said central opening, said walls being arranged with the flange of the upper wall telescoped upon the flange of the lower and the lugs of the lower wall contacting with said upper wall.

In testimony whereof I affix my signature.

LEMOTT D. HUBBARD.
